UNITED STATES PATENT OFFICE.

FRANCIS DE GRUCHY, OF NEWARK, NEW JERSEY.

STOKER OR MOVING GRATE.

Application filed April 25, 1924. Serial No. 709,060.

To all whom it may concern:

Be it known that I, FRANCIS DE GRUCHY, a citizen of United States of America, residing at Newark, in the county of Essex and State of New Jersey, have invented new and useful Improvements in Stokers or Moving Grates, of which the following is a specification.

This invention relates to improvements in stokers or moving grates and has for its primary object, the provision of a grate made up of a plurality of grate sections, mounted upon a grate bar, and each section including a surface plate which may be removed from or applied to the grate bar without dumping the fire or causing the stopping of the stoker.

Another object of the invention is to provide a surface plate which is provided with a plurality of openings so arranged as to render the plate free from all "dead spots" or plugged holes and which permits the draft from beneath the stoker to penetrate the entire surface of the plate, thus assuring a complete consumption of the fuel during its passage through the fire box.

A further object of the invention is to provide a grate section which includes a surface plate which is interchangeable with respect to the supporting grate bar, whereby surface plates having different size openings may be substituted depending upon the size of coal to be used.

A still further object of the invention resides in the provision of a means for permitting rocking movement of the surface plate with respect to the grate bar whereby to permit the surface plate to move a slight distance in order to pull away from the next adjacent surface plate when passing over the sprocket wheels of the stoker.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a view showing a stoker embodying my improved grate sections.

Figure 2 is a fragmentary top plan view of a portion of the stoker.

Figure 3 is a perspective view of one of the grate sections mounted upon a grate bar.

Figure 4 is a vertical sectional view on the line 4—4 of Figure 3.

Figure 5 is a sectional view on the line 5—5 of Figure 3.

Figure 6 is a detail perspective view of the surface plate and the carriage for supporting the same.

Figure 7 is a sectional view through one of the end grate sections.

Referring more particularly to the drawing, the reference numeral 10 designates a stoker grate in its entirety and which is usually mounted for passage through a furnace 11. A hopper 12 is disposed at one end of the grate and serves to feed fuel in the nature of coal to the grate. The furnace and hopper do not constitute a part of the invention but have been shown to illustrate the application of my invention.

The stoker grate 10 in the present instance is shown as comprising pairs of sprocket wheels 13 over which pass endless chains 14. Power may be imparted to the sprocket wheels in any suitable manner in order to cause movement of the chains. Bolted as at 15 to the chains 14 are transverse grate bars 16, and mounted on each grate bar are a plurality of grate sections 17 and disposed at the ends of bars are end grate sections 18. There are sufficient number of these grate sections to fill the space between the ends of the grate bars, and the number of sections depending on the width of the stoker.

Each of the grate sections 17 comprises a base 19 cast in a single piece and provided with a pair of spaced upstanding walls 20. The walls 20 are each provided with aligned seats 21 for the reception of a pair of tubular rails 22. The rails 22 are held in their seated position by plates 23 which are bolted or otherwise secured as at 24 to the base. The base is removably attached to the grate bar by a bolt and nut connection 25, the bolt of which passes through one of the usual slots 26 in the grate bar and through a slot 26' in the base, the head of the bolt being prevented from turning movement by a pair of walls 27' which extend the length of the slot 26. A carriage 27 is slidably mounted on the tubular tracks 22 and is formed with spaced upright walls 28 provided with openings 29 through which the tubular tracks pass. The openings 29 are slightly larger than the diameter of the tracks to permit the carriage to rock a slight

distance when passing over the sprockets for a purpose to be presently explained. Each wall 28 is provided with a pair of studs 29' for reception in recesses 30 formed in the underside of the surface plate 31. The surface plate 31 is formed with equidistantly spaced openings 32, and the recesses 30 are interposed between certain of these openings. The openings are so arranged that no "dead spaces" appear on the face of plate whereby a draft from beneath the grate is permitted to pass through the entire surface plate for effecting a complete consumption of the coal. An opening 33 is formed centrally of the plate and through which a bolt 34 passes for threaded engagement with an opening 35 formed in the carriage 27. The bolt 34 permits the ready removal of the plate and connects the surface plate with the carriage 20 for rocking movement therewith in one direction and for sliding movement therewith in a direction at right angle to the rocking movement. This sliding movement permits the surface plates to be moved flush against each other and permits of the expansion and contraction of the plate with respect to its supporting structure. The front of the surface plate 31 is formed with a trough 35' and the opposite end of the plate is beveled as at 36. The trough 35' is provided with lugs 37 for receiving the end of the preceding surface plate. It will be understood that the trough catches the ashes which may drop between the surface plate when the plates separate as they pass over the sprocket wheels as shown in Figure 1 of the drawing.

Should the grate bar 16 become warped, which warping will tend to throw the surface plates out of horizontal alignment with respect to each other, I provide an adjusting means in the form of set screws 38 having threaded engagement in the corners of the base. By adjusting the set screws, the level 45 of the surface plates may be brought into perfect horizontal alignment at all times.

From the foregoing description, it will be seen that I have constructed a grate section which permits the entire consumption 50 of the fuel contained on the surface plate. Furthermore, the surface plates may be easily removed when the stoker is in motion by removing the bolt 34. When applying the plate, the studs 29 are seated in the recesses 30 and when in position serve to align the opening 33 in the surface plate with the threaded opening 35 in the carriage 55 to permit the ready insertion of the bolt 34. The opening 33 is slightly larger than the diameter of the bolt to permit circulation 60 of air therethrough for supplying the proper draft of the coal about said openings. It will be seen that as the grate sections pass downward over the sprockets at the end of 65 the stoker, the surface plate will rock with

the carriage to permit the next adjacent grate section to separate therefrom and which tends to prevent a binding action between the sections at this point. The carriage being slid able allows for the expansion and contraction in a transverse direction and permits the surface plates to be brought into contact with each other. By providing the tracks of tubular material, it will be seen that the draft is permitted to pass therethrough for cooling the tracks. 70

Each end grate section 18 comprises a surface plate 39 of a construction similar to the surface plate 31 but is provided with a depending bracket 40. The bracket 40 is provided with a square opening 41 for the reception of a square nut 42 which nut has threaded engagement with a bolt 43 passing through one of the slots 26 in the grate bar. These surface plates may be removed by unscrewing the bolt 43 from its connection with the nut 42. 80

While I have described what I deem to be the most desirable embodiment of my invention, it is obvious that many of the details may be varied without in any way departing from the spirit of my invention and I therefore do not limit myself to the exact details of construction herein set forth nor to anything less than the whole of my invention 95 limited only by the appended claims. 90

What is claimed as new is:—

1. In a stoker grate, a grate bar, a grate section including a base, means for removably securing said base to said grate bar, a surface plate, and means for mounting said surface plate for movement on said base, said last means comprising a pair of tracks supported by said base, and a carriage slid able on said tracks upon which said surface plate is removably supported. 100

2. In a stoker grate, a grate bar, a grate section including a base, means for removably securing said base to said grate bar, a surface plate, and means for removably mounting said surface plate for movement on said base, and means for adjusting the level of said surface plate with respect to said grate bar. 110

3. In a stoker grate, a grate bar, a grate section including a base, means for removably securing said base to said grate bar, a surface plate, tracks mounted above said base, a carriage slid able on said tracks, an opening arranged centrally of said surface plate, a bolt passing through said opening for co-action with the threaded opening in said carriage for removably securing said surface plate with said carriage, and means for centering said opening for the insertion 120 of said bolt. 115

4. In a stoker grate, a grate bar, a base removably secured to said grate bar, a pair of tracks mounted above said base, a carriage movably mounted on said tracks, a 130

surface plate, and means for removably securing said surface plate to said carriage.

5. In a stoker grate, a grate bar, a grate section including a surface plate, means for removably mounting said grate section on said grate bar, means for permitting the sliding movement of said surface plate in one direction, and means for permitting rocking movement of said surface plate in

a direction at right angles to the sliding movement, said last means including a pair of tracks and a carriage connected to said surface plate and loosely mounted on said tracks.

In testimony whereof I have affixed my signature.

FRANCIS DE GRUCHY.
